UNITED STATES PATENT OFFICE.

ARTHUR LEONARD WHEELDON, OF LONDON, ENGLAND, ASSIGNOR TO DEAN'S RAG
BOOK COMPANY, LIMITED, OF LONDON, ENGLAND.

STUFFED DOLL.

1,262,417.

Specification of Letters Patent.

Patented Apr. 9, 1918.

Application filed January 30, 1917. Serial No. 145,478.

To all whom it may concern:

Be it known that I, ARTHUR LEONARD WHEELDON, a subject of the King of Great Britain, residing at London, England, have 5 invented certain new and useful Improvements in Stuffed Dolls, of which the following is a specification.

In stuffed dolls and like toys or sheets for making up into stuffed dolls and toys, it has 10 been usual to print or construct the front of the body and leg and front part of the foot in one piece, the back of the body and leg and back part of the foot in another piece, and the sole of the foot as a third 15 piece, these three pieces being sewn together at their edges with the printed side of the figure face to face. It has been usual to then turn such sewn article inside out so as to bring the printed surfaces outside after 20 which the article is stuffed to form the doll. Now the object of this invention is to print or construct the foot of the doll or toy in such a way that the separate sole piece is not required and that the foot is easier to 25 make up and is given a better shape than when the separate sole is used.

My invention will be clearly understood from the following description aided by the annexed drawings in which:—

30 Figure 1 is a front elevation of a doll constructed in accordance with my invention. Fig. 2 is a side elevation thereof.

Fig. 3 is a view of sufficient of the front of a leg and foot ready for sewing and

35 Fig. 4 is a similar view to Fig. 3 but of the back of the leg and foot, and

Fig. 5 is an under view of the sole of the foot when made up.

According to this invention I print or cut 40 out the front of the foot 1 of a shape as will be seen in the drawings, the leg portion 2 broadening from about the ankle to points 3 and then narrowing inward by two curves shown by the lines 4, which indicate the 45 cutting edge and which meet at about the center 5, which is somewhat below the plane of the points 3.

The back of the foot is printed or cut out somewhat similarly, see Fig. 4, except that 50 the center 5 is approximately in the same plane as the points 3.

In making up the doll I place the sheets with the printed side face to face as usual

and with regard to the body, arms and head conduct the operations in the usual manner. 55

In connecting the lower part of the leg and the foot pieces together I first connect the front and back portions by sewing them together along the lines 8, 8 and 8, 8. I then draw in the part marked 9 and sew together the two edges of the dart thus formed along the dotted lines, after which I sew the two pieces of the foot together along the lines 6, 6 and 7, 7, from the points 3^a, 5^a, and 3^b, and then turn the foot and legs with 60 the body inside out as is usual, the result being that the foot portion will be a more correct imitation of shape of a foot than when the sole is sewn on separately. The 65 article is finally stuffed as usual. 70

The feet may be ornamented and colored in any suitable manner to represent a boot, sock or foot and the invention may be applied to feet of animals where suitable.

What I claim and desire to secure by 75 Letters Patent is:—

A rag doll, having each leg thereof constructed of a pair of separate blanks arranged face to face, one for the front of the leg and the other for the back, and stitched 80 together continuously along their marginal edges with the seam lines following the contour of the blanks; the blanks of each pair first broadening from the ankle portion along outwardly-directed, symmetrically- 85 curved lines which terminate at oppositely-located points, and then narrowing from the first-named points along inwardly-directed, symmetrically-curved lines which meet at a point midway between said first-named 90 points, whereby the portion of the blanks between the adjacent first and second-named curved lines will form the complete foot of the corresponding leg, with the seams positioned crosswise under the foot; each front blank 95 being drawn inward at the ankle portion thereof to form a transverse dart, the edges of which are sewn together so as to define the ankle.

In testimony whereof I have hereunto set 100 my hand in presence of two subscribing witnesses.

ARTHUR LEONARD WHEELDON.
